(57) **CLAIM**

The ornamental design for a pair of gaming computer speakers as shown and described.

DESCRIPTION

FIG. 1 is a front, left and top perspective view of a pair of gaming computer speakers showing my design.

FIG. 2 is a front, left and top perspective view of a speaker of the pair of gaming computer speakers of FIG. 1.

FIG. 3 is a rear, right and bottom perspective view of the speaker of FIG. 2.

FIG. 4 is a front elevation view of the speaker of FIG. 2.

FIG. 5 is a rear elevation view of the speaker of FIG. 2.

FIG. 6 is a left side elevation view of the speaker of FIG. 2.

FIG. 7 is a right side elevation view of the speaker of FIG. 2.

FIG. 8 is a top plan view of the speaker of FIG. 2.

FIG. 9 is a bottom plan view of the speaker of FIG. 2.

FIG. 10 is a front, left and top perspective view of another speaker of the pair of gaming computer speakers of FIG. 1.

FIG. 11 is a rear, right and bottom perspective view of another speaker of FIG. 10.

FIG. 12 is a front elevation view of another speaker of FIG. 10.

FIG. 13 is a rear elevation view of another speaker of FIG. 10.

FIG. 14 is a left side elevation view of another speaker of FIG. 10.

FIG. 15 is a right side elevation view of another speaker of FIG. 10.

FIG. 16 is a top plan view of the other speaker of FIG. 10; and,

FIG. 17 is a bottom plan view of another speaker of FIG. 10. The broken lines shown in the drawings are included for the purpose of illustrating portions of the pair of gaming computer speakers that form no part of the claimed design.

1 Claim, 17 Drawing Sheets
